GUILFORD NORTON, OF BOSTON, MASSACHUSETTS, ASSIGNOR TO
PHILOMELA T. Vining, OF NEW YORK CITY.

Letters Patent No. 87,109, dated February 23, 1869.

IMPROVEMENT IN ANCHORS.

The Schedule referred to in these Letters Patent and making part of the same.

To all whom it may concern:

Be it known that I, GUILFORD NORTON, of Boston, in the county of Suffolk, and State of Massachusetts, have invented a new and improved Anchor; and I do hereby declare that the following is a full, clear, and exact description of the same, reference being had to the accompanying drawings, in which—

Figure 1 is a top view of the anchor.

Figure 2 is a side view of the anchor.

In the said drawings—

A represents the stock.

B B represent the flukes.

C C represent the palms.

D represents the shank.

The first part of my invention consists in forming the stock of an anchor with a "bow," by adding, to each end of the stock of an ordinary anchor, a piece of metal, which is bent forward, and fastened to the shank, near the part where the flukes are attached, as shown in fig. 1. The chief advantage of this arrangement is that it prevents the cable from fouling around the stock, as there are no ends for it to catch upon, prevents chafing against the vessel when the anchor is suspended at the bow, and affords a good hold for a grappling-iron.

The second part of my invention consists in the pe-

culiar construction of the hinged flukes, and that portion of the shank to which they are attached, whereby each fluke has a double bearing against the shank, when a strain is brought upon the anchor. The flukes are attached to the shank by grooves in the flukes, and feathers upon the shank, with pins passing through them, the bearings *r* and *n* being respectively against the feather and the main body of the shank, as shown by the drawings. By this means, the requisite strength is given to enable the flukes to bear the strain to which they are subjected, all strain being taken from the pins.

The third part of my invention consists in constructing the palms with perforations, *a*, one on each side of the flukes, for the purpose of affording a ready hold, when it is desired to fish the anchor.

Having thus described my invention,

What I claim, is—

Not either of the devices singly, but the combination, in an anchor, of the hinged flukes B, stock A, and shank D, when constructed as shown, and for the purpose specified.

GUILFORD NORTON.
